Attns.

UNITED STATES PATENT OFFICE

GEORG QUITSCHALLE, OF PANKOW, NEAR BERLIN, GERMANY

SUSPENSION DEVICE FOR FIRE EXTINGUISHERS

Original application filed July 7, 1927, Serial No. 204,080, and in Germany July 21, 1926. Divided and this application filed November 26, 1928. Serial No. 322,028.

This invention relates to a suspension device for portable, as well as manually operable fire extinguishing apparatus and is a division of my United States application, Serial Number 204,080, filed July 7, 1927. The invention has for its object to provide an approved suspension device for fire extinguishing apparatus including a blow bolt for use in the manual operation of the extinguishing apparatus in combination with a hinged member normally supporting the blow bolt in inoperative position but being capable of being swung laterally to a position to permit manual depression of the blow bolt.

The invention is illustrated diagrammatically and by way of example on the accompanying drawings in which the upper part of Figure 1 shows a vertical section through the suspension device and the lower part is a side-view of an extinguishing apparatus suspended from said device, whereas Figure 2 is a representation of a complete fire extinguishing plant in which the extinguishing apparatus is suspended from said suspension device.

In Figure 1 *m* denotes a vertical plate affixed to a wall (Fig. 2) separating a room in which the extinguishing apparatus is housed from the room in which a fire could arise. A T-shaped member *n* is affixed to the wall *m*. The vertical part of this member is hollow and the extinguishing apparatus is suspended from the lower half of this hollow part, for instance by means of lateral pins *o* projecting forth from the neck of the closing cap *j* of the receptacle *a* and engaging suitably located and shaped slots in the lower end of the member *n*. These slots are open also laterally, but here covered with a sleeve *n'* encompassing said lower end and contacting with a packing ring *p* provided upon the cap *j* so that the extinguishing liquid escaping eventually through the orifice *k* cannot escape at the lower end of the member *n*.

I prefer to have the apparatus carried also by a clip *n*² affixed to the wall plate *m*. *i* denotes a tubular mandrel, the upper end of which is closed by a thin sheet-metal piece *s'* which is inserted into a collar *s* and can be

pierced through by the lower pointed end of a mandrel *r* located in the hollow part of the T-shaped member *n* guided by a partition wall provided therein. Above this mandrel, laterally from it, is provided a small cartridge *t* connected with a fuse cord *z*, and just above the mandrel *r* is a blow-member *u* which is provided with a shank 10 engaged and normally held in raised position by an arm *v* hinged to the wall plate *m* as at 11.

If a fire should break out the fuse *z* which establishes a connection between the respective room and the fire-extinguishing apparatus will be ignited and the ignition will be propagated to the cartridge *t*. The gas under pressure produced by the ignition of the cartridge drives the mandrel *r* down by pressing forcibly and suddenly upon the top disk *r'* of the same, whereby the sheet-metal piece held by the collar *s* will be pierced. Instantly thereafter the gas under pressure will rush into the tubular mandrel *i* and act upon certain members located in the top of the vessel *a* which is filled with a fire extinguishing liquid surrounding a cartridge adapted to produce a gas by which said liquid will be driven upwardly into the tubular mandrel or tube *i*. The members located in the top of said vessel *a* are shown and described in my United States patent application concerning especially the fire extinguishing apparatus proper, Serial Number 204,080, filed July 7, 1927. The large amount of gas under pressure now generated will force the extinguishing liquid through the tube *i* into the lower chamber of the vertical part of the T-piece *n*, and then further through the pipe *w* and its branches to the sprays *y*, Fig. 2, through and by which said liquid will be thrown upon the fire and extinguish it. *z*, Fig. 2, denotes branches of the fuse *z* (Fig. 1).

The apparatus when attached to the wall may be operated nevertheless also manually. It is merely necessary to turn the arm *v* aside when the blow member *u* will be free to be knocked down upon the mandrel *r* *r'*, the effect being then the same as if the cartridge *t* would have been exploded, in that the sheet-metal piece *s* will be pierced and the force of the blow transmitted to the tube or

hollow mandrel *i* and further through the rod *g* of the cartridge *c*, by the intermediary of the bottom of the cartridge closing member *d*.

I claim:

5 A suspension for fire extinguisher apparatus comprising a hollow member adapted to receive an extinguisher apparatus, a blow bolt movable in said hollow member, a hinge member engaging and normally retaining the blow bolt in inoperative position and adapted
10 to swing laterally to release said blow bolt.

In testimony whereof I affix my signature.
GEORG QUITSCHALLE.
